DRAINAGE TYPE COAL BUNKER GATE
William G. Davenport, Jenkintown, Pa., and Edward C. Addison, Laurel Springs, N.J., assignors to Beaumont Birch Company, Philadelphia, Pa., a corporation of Pennsylvania
Filed Mar. 8, 1960, Ser. No. 13,629
9 Claims. (Cl. 193—21)

This invention relates to overhead bunker coal gates, and more particularly relates to improved apparatus for handling the coal wash water so as to completely eliminate any possibility of water drippage onto the floor below or onto personnel working beneath the coal gates.

The coal as discharged into the coal bunker contains a large amount of wash water which had been used repeatedly at the mines so that this water has an acidity of approximately 2.2 and is, therefore, quite corrosive. The corrosive nature of the water thus renders it important that any drainage system utilized should operate reliably and without leaks to eliminate the hazard to personnel and the possibility of damage to the floor.

In the past, drainage apparatus has been employed utilizing a pipe pivoted through the side of the bunker swingable closure gate proximate its bottom. By this arrangement, the drainage water would pass from the bunker into the pipe and be conducted to a run-off gutter. This apparatus has proved, however, to be unsatisfactory because drain pipes of any practical size soon became clogged with the silt in the drainage water, and moreover, the pivotal coupling of the pipe to the bunker closure gate also failed due to corrosion caused by the highly acid drain water.

The present invention overcomes these problems by eliminating the drain pipe altogether. As will presently be seen, the apparatus according to the invention causes the drain water to drip over the front edge of the bunker closure gate and onto an inclined swingable trough, which trough directs the water into a fixed position run-off system. The inclined trough is coupled to the bunker closure gate in such a manner that it is swung outward and upward away from the discharging coal when the gate is opened so that the trough does not become clogged with coal. Means are also employed to prevent coal from being thrown onto the swingable trough as it moves downward and inward while the bunker closure gate is closing against the flow of coal out of the bunker. Accordingly, it is a primary object of this invention to provide a novel bunker gate drainage apparatus which is not subject to silt clogging or failure due to corrosion as occurred in the past with pipe type drainage systems.

Another object of this invention is to provide a novel bunker gate drainage apparatus which includes a shiftable trough for collecting the drain water from the bunker gate and directing it into a run-off system.

Yet another object of this invention is to provide a novel bunker gate drainage apparatus having a specially configured bunker closure gate which allows the drain water to escape over one edge thereof onto a shiftable trough.

Still another object of this invention is to provide a novel bunker gate drainage apparatus as aforesaid which includes coal directing structure for controlling the flow of coal from the bunker to prevent discharging coal from clogging the shiftable trough.

The foregoing and other objects of the invention will become apparent from a reading of the following specification in conjunction with an examination of the appended drawings, wherein:

FIGURE 1 illustrates the apparatus according to the invention in organization with its associated environmental equipment, and shows one view of a coal bunker, under-

2

lying coal larry, and the bunker gate and drain system together with the gate operating mechanism;

FIGURE 2 is an elevational view of the apparatus as would be seen when viewed along the lines 2—2 of FIGURE 1;

FIGURE 3 is a sectional view of the apparatus as would be seen when viewed along the lines 3—3 of FIGURE 1, some parts being shown in section and other parts in elevation;

FIGURE 4 is an enlarged fragmentary view of the interrelationship of portions of the coal bunker, closure gate and shiftable drain trough when the gate is in closed position, some portions being shown in section and other portions in elevation;

FIGURE 5 is a fragmentary bottom view of the bunker closure gate and drain apparatus according to the invention;

FIGURE 6 is an end elevational view of the upper part of the apparatus of FIGURE 1 as viewed from the right, with certain parts sectioned away to show interior details;

FIGURE 7 is a perspective view of the bunker closure gate with one side wall partially broken away to show the gate drip ledge;

FIGURE 8 is an enlarged view of the bunker gate, drain apparatus and gate opening mechanism showing the several components in their respective inter-relationship with the gate closed;

FIGURE 9 is similar to FIGURE 8 except that it shows the several components in their respective inter-relationship with the gate open;

FIGURE 10 is an enlarged fragmentary view of an adjustable position coal baffle secured to the bunker chute and as is seen within the phantom circle of FIGURE 9.

In the several figures, like elements are denoted by like reference characters.

Referring now to the drawings and firstly to FIGURES 1, 2 and 3 for an understanding of the general organization into which the novel drainage apparatus is to be

incorporated, there will be seen an overhead coal bunker 20 having secured to and depending therefrom a four-sided open bottomed chute 21, the bottom of which chute is closed by a swingable gate 22 pivotally secured on opposite sides of the chute as by the pivots 23. Underlying

the chute 21 and closure gate 22 there will be seen a coal larry having a hopper 24 fixedly secured to the angle and channel framing members 25 and 26, the entire larry being mounted upon the axles 27 carrying the single flanged wheels 28 which are seated upon and ride along the underlying fixed track structure 29. Secured to and

depending from the larry framing members 26 are the vertical struts 30 which carry a transversely extending horizontal strut 31 to which is affixed an index member 32 which moves with the larry. Fixedly secured to the

tracks 29 is a second indexing member 33 so positioned relative to the bunker chute 21 that when the index members 32 and 33 are aligned with one another the larry will be centered beneath the bunker chute.

Secured to and extending upward from one of the framing members 26 are a pair of brackets 34 each of which carries a bearing 35 for supporting at opposite ends a rock shaft 36 having a gate operating hook 37 fixedly secured thereupon substantially centrally along the length of the larry. Also fixedly secured upon the rock shaft 36

at one end thereof is a sprocket 38 having a chain 39 trained thereover and extending downwardly therefrom. When the chain 39 is operated from below, the sprocket 38 is rotated, carrying with it the rock shaft 36 and the gate operating hook 37 to open and close the bunker chute closure gate in a manner to be now described.

Secured to and depending from the top of the bunker chute 21 is a trapeze-like hanger having a pair of verti-

cally depending hanger arms 45 spaced upon opposite sides of the chute 21 and to the bottom ends of which are secured opposite ends of a horizontal rod as at 47, which rod carries rotatably mounted thereupon a roller sleeve 46. Seated transversely upon the roller 46 and extending in opposite directions laterally therefrom are a pair of gate operating pull bars 40 pivotally secured to the sides of the closure gate 22 at the fore end thereof by the pivots 41. Bridging between the pull bars 40 at the ends thereof opposite the pivot connections 41 in parallel relationship to one another are a pair of rod mounted rollers 42 and 43, the rods upon which the rollers are mounted being secured to the pull bars as at 44.

As best seen in the showings of FIGURES 8 and 9, when the hook 37 is rotated by means of the rock shaft 36, the sprocket 38 and chain 39, the hook finger 48 passes upward between the rollers 42 and 43, engaging the roller 42 and drawing the pull bars 40 over toward the left to thereby swing the closure gate 22 about the pivots 23 and open the bottom of the chute 21 so that the bunker stored coal may drop into the larry hopper 24 positioned beneath the chute. When the desired amount of coal has been deposited into the larry hopper, for example as determined by a weight scale (not shown), the gate 22 is again closed by rotating the hook 37 in the opposite direction so that the underside of the hook 37 bears against the roller 43 to push the pull bars 40 to the right and swing the gate 22 again into its closed position. Continued clockwise rotation of the hook 37 completely disengages it from between the rollers 42 and 43 so that the larry may be moved out from under the chute 21 for purposes of depositing the coal contained therein into remotely located stoker mechanisms associated with boilers or furnaces or similar coal consuming apparatus. With the larry removed from beneath the bunker chute 21 it will be apparent that the gate 22 may not be operated to open since the hook 37 is completely removed from operative association with the roller 42, having been carried away from the chute region entirely when the larry is moved out from thereunder.

Understanding now the basic operation and organization of the larry operated coal bunker, attention may now be directed toward the novel apparatus according to the invention incorporated into the aforescribed structures for carrying off the coal drain water. As is most clearly seen in FIGURES 1, 8 and 9, a fixed position run-off gutter 48, supported at intervals by supports 49, runs horizontally past the bunker chute 21 laterally off to one side thereof so as to occupy a non-interfering position relative to the path of motion of the coal larry. A fixed position inclined trough 50 is supported from the bunker 20 by means of the angle brackets 51 and the turn buckle adjusted hanger rods 52 so that the lower edge of the inclined trough 50 lies above the run-off gutter 48, any water collected by the trough 50 being, of course, directed into the gutter. The trough 50 is pivotally secured to the brackets 51 as at 53 and the lower section of the hanger rods 52 as at 54. By adjustment of the turn buckles 55 to lengthen or shorten the hanger rods 52 a certain degree of trough 50 slope adjustment is obtained, such adjustment being relatively non-critical. It will be observed that the fixed trough 50 is laterally displaced from the bunker chute 21 and gate 22 so that, as best seen in the showing of FIGURE 9, coal discharging from the bunker chute is precluded from being thrown onto the trough 50 and eventually clogging it. Some means must, therefore, be utilized for catching the drain water and directing it onto the fixed trough 50 when the gate 22 is in its closed position beneath the bunker chute 21.

To this end, a swingable drain trough 56 is employed, the trough 56 being mechanically linked to the chute 21 and gate 22 by a lever system so that the swingable trough 56 is placed in functioning position when the gate 22 is closed and is swung out of the way when the gate is open.

The lever system employed for swinging the drain trough 56 from operative to inoperative position includes the lever arms 57 and 58 and the brackets 59, the lever arms 58 being pivotally secured to opposite sides of the gate 22 as at 60 and similarly pivotally secured to the upper end of the lever arms 57 as at 61. The lower end of each lever arm 57 is fixedly secured respectively to the opposite side walls of the swingable trough 56 and each arm 57 is pivotally secured as at 62 intermediate the arm ends to the brackets 59, the latter being fixedly secured to one side wall of the bunker chute 21.

The pivoted lever arms 58 each include a threaded rod section 63 so that the arm length may be adjusted to properly position the upper edge 64 of the swingable trough 56 beneath the drip ledge 65 of the swingable closure gate 22. The operation of the swingable trough 56 is clearly illustrated in the showings of FIGURES 8 and 9 wherein it is observed that opening of the gate 22 by means of the pull bars 40 and hook 37 previously described causes the pivoted lever arms 58 to be drawn toward the left to thereby swing the trough 56 upward and to the right about the fixed pivot points 62 associated with the brackets 59. Thus, in the open gate position, the swingable trough 56 is removed from the region of the discharging coal to prevent clogging thereof, and swings inward into proper operating position as the gate 22 closes toward the right to cut off the flow of coal out of the bunker chute 21.

As the gate 22 closes toward the right against the downward flow of coal out of the bunker chute 21, the coal flow similarly tends to shift somewhat toward the right and would, unless prevented, discharge a certain amount of coal onto the inwardly swinging trough 56. In order to prevent this condition from arising, the lower portion of the side wall of the bunker chute 21 which is proximate the drain trough system is turned inwardly toward the center of the chute, as at 66. This inward turned lower portion 66 of the bunker chute 21 terminates at a point below the corresponding lower edge 67 of the chute opposite side wall and thus lowers the flow line of the coal and shifts it inwardly toward the chute center to a sufficient degree to prevent emerging coal from being thrown upon the in-swinging trough 56, even though the altered coal flow line tends to move toward the right as the gate 22 closes against the coal flow. Additionally provided to deflect any maverick coal downward and away from the inwardly swinging trough 56 is a baffle plate 68 pivotally suspended from a shaft 69 by means of a pair of hanger straps 70, the shaft 69 being secured at opposite ends to the chute mounted brackets 59 as for example shown at 71 in FIGURE 6. Projected through the plane of the baffle plate 68 is a baffle position stop assembly including the bolt 72 and nuts 73 by means of which the angle assumed by the baffle plate 68 relative to the chute 21 may be adjusted within limits.

Understanding now the basic operation and organization of the improved drainage system, attention will be directed to certain details of the apparatus best seen in the showings of FIGURES 3 through 7. Considering first FIGURES 4 and 7 which show most clearly the drip ledge structure of the leading edge of the closure gate 22, it is observed that the gate drip ledge 65 comprises an edge thickened portion 74 having grooves 75 formed on the undersurface thereof and extending the full width of the gate 22. When the gate 22 is in closed position, the coal drain water settles to the bottom of the chute 21 and collects in the hollow formed by the curved gate bottom 76 and upwardly extending gate sides 77, the water level rising until it reaches the upper edge 78 of the drip ledge 65.

It will be noted that the gate 22 is so designed that when it is in its normally closed position, as best shown in FIGURES 1 and 8, the upper edge 78 of the drip ledge is disposed at a somewhat lower level than is the opposite edge 79 of the curved gate bottom 76, thereby favoring the

drainage of water from the gate in only one direction, namely outwardly across the upper edge 78 of the drip ledge 65. In order to insure such normal closing position of the gate 22, the latter is provided with suitable stop means operative to limit swinging of the gate in the direction of its closing movement and so prevent its assuming a position which would permit unintended drainage of water across the edge 79 of its curved bottom. Preferably, this stop means comprises a rod 80 extending transversely across the gate having its opposite ends secured to the opposed gate walls as at 81-81.

This stop rod 80 is disposed externally of the chute 21 so that when the gate moves into its closed position the rod engages the proximate wall of the chute to limit further closing movement of the gate relatively to the chute. It will be observed that the stop rod 80 is spaced a distance above the curved bottom 76 of the gate sufficient to permit the free discharge of coal particles from the gate by way of the space so provided between the stop rod and the gate bottom. Correct spacing of the stop rod relatively to the gate bottom is of importance not only to prevent any possibility of such packing of the coal particles at the trailing end of the gate as might tend to prevent complete closing thereof (it being apparent that as the gate swings into its closed position any coal collected thereon outside the confines of the chute would be caused by the latter to be pushed off of the gate beneath the stop rod 80), but also to accurately relate the gate movement to that of the swingable trough 56. It will be apparent, of course, that the stop rod accurately determines the proper closing position of the gate 22 relatively to the chute 21 and thus, upon proper adjustment of the interconnecting linkages between the swinging gate and the swinging trough, the water drainage edge 78 of the gate, when the latter is fully closed, is exactly in the correct position relatively to the swingable trough 56 for effective drainage of the water from the gate into said swingable trough 56 and thence into the fixed trough 50.

The continued rise of the drain water in the gate bottom causes an overflow condition so that the water runs over the drain ledge upper edge 78 and downward into the swingable trough 56, the upwardly recessed grooves 75 formed on the bottom of the thickened edge portion 74 preventing the drain water from running down along the curved gate bottom undersurface to its lowest point to drip therefrom onto the floor below. The sloping angle of the swingable trough 56 directs the collected drain water down into the fixed trough 50 from which it is channeled into the run-off gutter 48. As best seen in the showing of FIGURE 4, the upper edge of the swingable trough is turned upward as at 64 to engage the undersurface of the gate bottom 76 and provide a closure which helps to prevent leakage of drain water due to splashing or water back-up when a relatively large flow of water is falling over the drip ledge. Finally, it is noted that the gate sides 77 are formed integrally with the gate bottom 76 and extend beyond the drip ledge 65 so that the drain water must pass over the edge of the latter and cannot escape sideways.

As best seen in FIGURES 3, 5 and 6 the swingable trough 56 extends beyond the ends of the gate drip ledge 65 in order that none of the drain water may escape. Similarly, the fixed drain trough 50 is of a width somewhat greater in extent than that of the swingable drain trough 56, although the inwardly angled sides 79 thereof do not necessarily have to take the form illustrated, but may be of any convenient configuration and need not be inwardly tapered at all. Finally, the inwardly turned lower edge section 66 of the bunker chute 21 need not be formed in the manner shown but might for example be achieved by the use of a baffle plate similarly oriented and fixed within a chute having completely vertical side walls.

Having now described our invention in connection with a particularly illustrated embodiment thereof, it will be

apparent that various changes and modifications will occur from time to time to those persons normally skilled in the art without departing from the essential scope or spirit of the invention, and, accordingly, it is desired to claim the same broadly as well as specifically as indicated by the appended claims.

What is claimed as new and useful is:

1. A drain water collecting apparatus for use in conjunction with an open-bottomed bunker discharge chute and a chute bottom closure gate shiftable between chute opening and chute closing positions comprising in combination, a swingable drain trough pivotally secured to a pivot structure fixedly positioned relative to the discharge chute, said drain trough being inclined when the gate is in chute closing position so that the trough upper edge is disposed in underlying relationship to at least a portion of the gate bottom and the trough lower edge is disposed in overlying relationship to a fixed position water run-off system which latter is spaced laterally away from the chute, means coupled to and effective for pivoting said trough about said pivot structure to swing the trough away from the chute bottom when the gate is shifted away from chute closing position, and deflecting means interposing the swingable trough and the chute bottom, when the latter is open, effective to deflect stray particles of discharging material away from the trough and thereby prevent trough clogging, whereby, when the gate is closed drain water may pass from the gate to the underlying swingable drain trough and be directed therefrom into the run-off system, and when the gate is open the trough is swung away from the chute to prevent discharging material from being thrown thereupon, said fixed position pivot structure comprising a support bracket fixedly secured to the bunker discharge chute and extending laterally therefrom toward the fixed position water run-off system, the bracket being located above the drain trough and having an unsecured terminal portion carrying the pivotal support for the swingable trough, said drain trough being secured to the bracket carried pivot by a first arm secured to said trough at the arm lower end, said arm extending upward to the pivot connection and therebeyond, and said means for swinging said trough about said pivot comprising a second arm coupled at one end to said first arm above the pivot connection and coupled at its other end to the chute closure gate.

2. A bunker drain water collecting apparatus comprising in combination, a bunker having a discharge opening, a pivoted gate arranged to open and close said opening, said gate including first means for permitting escape therefrom of bunker drain water when said gate is closed, second means for pivoting said gate to open and close the bunker discharge opening, and drain water collecting third means operatively associated with said first means for collecting escaping bunker drain water when said gate is closed, said third means being physically displaced and operatively disassociated from said first means when said second means is actuated to open said gate, said bunker including discharge opening baffling means for directing the outward flow of bunkered material away from said drain water collecting third means to thereby prevent discharging material from clogging the latter, and auxiliary deflecting means interposing said third means and the bunker discharge opening when the latter is open effective to deflect stray particles of discharging material away from said third means to thereby assist in preventing clogging thereof.

3. A bunker drain water collecting apparatus comprising in combination, a bunker having a discharge opening, a pivoted gate arranged to open and close said opening, said gate including a drip ledge extending along one end of the gate bottom for permitting escape therefrom of bunker drain water when said gate is closed, means for pivoting said gate to open and close the bunker discharge opening, and a drain water collecting swingable trough

which underlies said drip ledge for collecting escaping bunker drain water when said gate is closed, said trough being physically displaced and operatively disassociated from said drip ledge when said gate pivoting means is actuated to open said gate, said drip ledge having formed on the undersurface thereof at least one horizontally extending upward recessed groove, whereby drip water is prevented from running to the undersurface of the gate bottom beyond the trough, said bunker discharge opening including baffling means for directing the outward flow of bunkered material away from said drain water collecting swingable trough to thereby prevent discharging material from clogging the latter, and auxiliary deflecting means interposing said swingable trough and the bunker discharge opening when the latter is open effective to deflect stray particles of discharging material away from said swingable trough to thereby assist in preventing clogging thereof.

4. In combination, a material-receiving bunker chute having a bottom discharge opening, a pivoted gate swingable relatively to said chute to open and close said discharge opening, the bottom of said gate being disposed in closely spaced underlying relation to the bottom edges of said bunker chute defining the discharge opening therefor and being of concave-up arcuate form to collect therein water drained from said material while said gate is in closed position, one end of said gate bottom having a drainage edge across which drainage water in excess of that retained by the closed gate may be discharged therefrom, means operatively associated with the gate for receiving the excess drainage water discharged from the closed gate and for directing it to a receiver remote from the bunker, said last-mentioned means including a drain trough which shifts toward the gate as the latter swings into its closed position and away from the gate upon swinging movement thereof into its open position, and deflecting means at the drain trough side of the bunker chute for preventing any substantial-impingement of the discharged material upon the drain trough as the latter moves relatively to the gate.

5. In the combination as defined in claim 4 wherein said deflecting means comprises a baffle pivotally suspended externally of the bunker chute immediately above and in closely spaced relation to the plane of movement of said shiftable drain trough.

6. In combination, a material-receiving bunker chute having a bottom discharge opening, a pivoted gate swingable relatively to said chute to open and close said discharge opening, the bottom of said gate being disposed in closely spaced underlying relation to the bottom edges of said bunker chute defining the discharge opening therefor and being of concave-up arcuate form to collect therein water drained from said material while said gate is in closed position, one end of said gate bottom having a drainage edge across which drainage water in excess of that retained by the closed gate may be discharged therefrom, means operatively associated with the gate for receiving the excess drainage water discharged from the closed gate and for directing it to a receiver remote from the bunker, said last-mentioned means including a drain trough which shifts toward the gate as the latter swings into its closed position and away from the gate upon swinging movement thereof into its open position, and stop means for limiting movement of the gate in the direction of its closing including an element fixed to the gate externally of the wall of the bunker chute remote from the drainage side thereof and adapted to engage said wall when the gate is closed, said element being operative to permit material on the gate to be swept therefrom as the gate moves in closing direction across the bottom edge of the bunker chute.

7. In combination, a material-receiving bunker chute having a bottom discharge opening, a pivoted gate swingable relatively to said chute to open and close said dis-

charge opening, the bottom of said gate being disposed in closely spaced underlying relation to the bottom edges of said bunker chute defining the discharge opening therefor and being of concave-up arcuate form to collect therein water drained from said material while said gate is in closed position, one end of said gate bottom having a drainage edge across which drainage water in excess of that retained by the closed gate may be discharged therefrom, means operatively associated with the gate for receiving the excess drainage water discharged from the closed gate and for directing it to a receiver remote from the bunker, said last-mentioned means including a drain trough which shifts toward the gate as the latter swings into its closed position and away from the gate upon swinging movement thereof into its open position, and stop means comprising a rod extending transversely across the end of the gate which is opposite that having said drainage edge for limiting movement of the gate in the direction of its closing, said rod being adapted to engage the wall of the bunker chute when the gate is fully closed and being further disposed at a level above the gate bottom sufficiently high to permit material on the gate to be swept therefrom beneath the rod as the gate moves in closing direction across the bottom edge of the bunker chute.

8. In combination, a material-receiving bunker chute having a bottom discharge opening, a pivoted gate swingable relatively to said chute to open and close said discharge opening, the bottom of said gate being disposed in closely spaced underlying relation to the bottom edges of said bunker chute defining the discharge opening therefor and being of concave-up arcuate form to collect therein water drained from said material while said gate is in closed position, said gate including a drip ledge extending along one end of the gate bottom for permitting escape therefrom of bunker drain water when said gate is closed, means for pivoting said gate to open and close the bunker discharge opening, and a drain water collecting swingable trough which underlies said drip ledge for collecting escaping bunker drain water when said gate is closed, said trough being physically displaced and operatively disassociated from said drip ledge when said gate pivoting means is actuated to open said gate, said drip ledge having formed on the undersurface thereof at least one horizontally extending upward recessed groove, whereby drip water is prevented from running to the undersurface of the gate bottom beyond the trough.

9. In combination, a material-receiving bunker chute having a bottom discharge opening, a pivoted gate swingable relatively to said chute to open and close said discharge opening, the bottom of said gate being disposed in closely spaced underlying relation to the bottom edges of said bunker chute defining the discharge opening therefor and being of concave-up arcuate form to collect therein water drained from said material while said gate is in closed position, said gate including a drip ledge extending along one end of the gate bottom for permitting escape therefrom of bunker drain water when said gate is closed, means for pivoting said gate to open and close the bunker discharge opening, and a drain water collecting swingable trough which underlies said drip ledge for collecting escaping bunker drain water when said gate is closed, said trough being physically displaced and operatively disassociated from said drip ledge when said gate pivoting means is actuated to open said gate, said drip ledge having formed on the undersurface thereof at least one horizontally extending upward recessed groove, whereby drip water is prevented from running to the undersurface of the gate bottom beyond the trough, and means intercoupling said gate, said bunker, and said drain water collecting trough effective responsive to gate opening actuation of said gate pivoting means to shift said trough out of operative association with said drip ledge, said intercoupling means comprising a pivoted linkage system including a first linkage arm pivotally cou-

pled to said gate at one arm end and pivotally coupled to one end of a second linkage arm at its other end, said second linkage arm being secured to said trough at its opposite end and pivotally connected to a support bracket at a point intermediate the ends of said second arm, said bracket being fixedly secured to the bunker structure, whereby, when said gate is opened said first arm pivots said second arm about the fixed bracket pivot and swings said trough away from said gate drip ledge and bunker discharge opening.
